GARMENT

Blanche Kruckow, Elmhurst, Ill., assignor to S & Z Manufacturing Company, Chicago, Ill., a copartnership

Application August 9, 1941, Serial No. 406,123

2 Claims. (Cl. 2—73)

The invention relates to improvements in garments especially adapted for female wear and has for its primary object the provision of an improved garment of the character indicated provided with a concealed pocket which is capable of ready access and highly efficient in use.

Other objects will appear hereinafter.

The invention consists of the combinations and arrangements of parts hereinafter described and claimed.

The invention will be best understood by reference to the accompanying drawing forming a part of this specification and in which

Fig. 1 is a front view of a slip equipped with a pocket embodying the invention;

Fig. 2 a rear view of the upper portion thereof, with portion broken away, to exhibit a rear view of the pocket arrangement;

Fig. 3 an enlarged section taken on line 3—3 of Fig. 1;

Fig. 4 an enlarged section on line 4—4 of Fig. 1; and

Fig. 5 an enlarged section taken on line 5—5 of Fig. 1.

The embodiment of the invention illustrated in the drawing comprises a slip 10 of conventional form and having its upper front portion formed of two pieces of material 11 and 12 secured to the lower skirt portion of the slip along the waist seam 13 and having their inner front portions overlapped as indicated. As will be observed the pieces 11 and 12 are tapered upwardly from the tops of their over-lapped portions to a peak and shoulder straps are secured to the peaks of said pieces. High darts or tucks 14 and 15 are extended upwardly from the seam 13 and the edges 16 and 17 of the front portions 11 and 12 respectively are secured as indicated to these darts or tucks thereby forming the sides of a pocket between the overlapping portions of the front portions 11 and 12. To effect this connection the edge of portion 11 is secured between the folds of the tuck 15 as indicated at the left of Fig. 3, and the edge of portion 12 is secured against the side of tuck 14 as indicated at the right of Fig. 3. The folds of tucks 14 and 15 are severed in the course of manufacture so that

these parts appear as separate parts in this view of the drawing. As will be noted the upper inner edges 17 and 18 of the front portions 11 and 12 are inclined inwardly and downwardly across the front of the top portion of the slip the edge 18 extending behind the portion 11 and being stitched thereto along the inclined seam 19 as indicated. The other inclined edge 17 is left free from the portion 12, thereby forming an upper downwardly and outwardly inclined open top for the pocket thus formed between the overlapping flaps of the portions 11 and 12 as will be readily understood. By forming the upper portions of the pieces 11 and 12 tapering upwardly to a peak and attaching shoulder straps to said peaks, the weight of objects in the pocket is evenly distributed to said shoulder straps and also serves to hold the opening of the pocket closed.

By this arrangement a concealed pocket is provided in a slip or undergarment for female wear which is of ready access and highly efficient in use. The specific form and arrangement of part is a simple and effective one for the purpose.

While I have illustrated and described a preferred form of construction for carrying my invention into effect this is capable of variation and modification without departing from the spirit of the invention. I therefore do not wish to be limited to the precise details disclosed but desire to avail myself of such variations and modifications as fall within the scope of the appended claims.

I claim:

1. A garment having its upper front portion formed of two over-lapping flaps extending upwardly from the waist portion and secured to each other around their edges except at one side of the top of one flap to provide an opening for the pocket thus formed, the upper portion of said flaps tapering upwardly from the tops of the over-lapped portions; and shoulder straps secured to the peaks of said tapered portions.

2. The garment specified in claim 1 in which a vertical tuck is formed in each over-lapping flap and the edge of the other flap secured thereto.

BLANCHE KRUCKOW.
